United States Patent Office

Des. 184,327
Patented Feb. 3, 1959

184,327

VEHICLE LUGGAGE CONTAINER

Elmo Paul Allen, Ankeny, Iowa, assignor to Charles W. Petersen, Somers, Iowa

Application June 25, 1958, Serial No. 51,536

Term of patent 7 years

(Cl. D14—27)

Fig. 1 is a front perspective view of a vehicle luggage container showing my new design therefor;

Fig. 2 is a rear perspective view with portions of an automobile in dotted lines for purpose of illustration only; and

Fig. 3 is a side view thereof.

I claim:

The ornamental design for a vehicle luggage container, substantially as shown and described.
